CLAIM

The ornamental design for a portable blender jar as shown and described.

DESCRIPTION

FIG. 1 is a perspective view of a portable blender jar showing the new design;

FIG. 2 is a front view thereof;

FIG. 3 is a rear view thereof; and,

FIG. 4 is a side view thereof.

The portions of the portable blender jar shown in broken lines form no part of the claimed design.

1 Claim, 4 Drawing Sheets
